CLASSIFIER

Charles E. Wood, Milwaukee, Wis.

Application May 19, 1937, Serial No. 143,408

2 Claims. (Cl. 209—465)

This invention relates to improvements in classifiers.

One of the primary objects of the present invention is to provide apparatus for achieving classification under relatively constant conditions and automatically discharging the oversize product with minimum liquid displacement and in very much reduced space.

More specifically, I propose to reduce the vertical height of conventional classification apparatus by confining the automatic discharge of solids to a hopper having very much less area than that of the entire bowl, the weight of the hopper contents being utilized to control automatic discharge therefrom. By the same means I avoid substantial losses of the liquid contents of the bowl proper and thereby tend to maintain conditions for classification in the bowl more uniform than heretofore. Uniformity of operating conditions is further promoted by an arrangement in which the rakes or raddles which are preferably employed to deliver the oversize solids to the discharge hopper, are operated at substantially the same speed in which the mass of water and suspended solids in the bowl are turning in a vortex produced in the delivery of the material thereto.

Other objects will appear from the following disclosure of the invention.

In the drawings:

30 Figure 1 is a vertical sectional view showing apparatus for the present invention.

Figure 2 is a fragmentary detail view of the discharge hopper in side elevation from a viewpoint at right angles to that of Figure 1.

35 Figure 3 is a plan view of the classification bowl and associated parts, the super-structure being removed.

Figure 4 is a fragmentary detail view on an enlarged scale showing in section similar to Fig. 1 the connection of the discharge hopper to the bowl.

Figure 5 is a fragmentary detail partially in plan and partially in section showing the attachment of the raddle arms to their actuating shaft.

45 Like parts are identified by the same reference characters throughout the several views.

The classification bowl 6 is of generally conventional form carried on any suitable supports in a horizontal position with the upper margins of its wall 7 horizontal for uniform discharge of liquid and undersize product throughout its periphery. The wall 7 of the classification bowl is preferably surrounded by a launder 8 with a discharge spout at 9 for delivery of the water and undersize product which overflows the margins 7

of the bowl. The supports shown in the drawings are purely for purpose of illustration.

The classification bowl 6 is centrally apertured and provided with a downwardly extending sleeve at 10 through which oversize solids may be discharged from the bowl. The sleeve projects into a hopper 15 carried by a sub-frame 16 and links 17 from a pair of scale beams 18. This arrangement provides for controlled vertical movement of the hopper with respect to the bowl. The annular diaphragm 20 marginally clamped to the bowl 6 about the opening therein and to the upper margin of the hopper, seals the hopper while accommodating this vertical movement with sub-frame 16 upon the scale beam.

The weight of the hopper and its normal content of oversize solids is counterbalanced by the weight carriers 21 adjustable on the scale beams 18 and respectively provided with the usual scale weights at 22. The scale beams preferably overlap and are loosely connected by a bolt at 23 which accommodates their necessary movement and at the same time serves as a fulcrum upon which link 24 is suspended for the actuation of the valve lever 25. This lever is pivoted in a 25 knife edge 26 engaging a bracket 27 carried by the hopper. The free end of the lever beyond its fulcrum supports a pin 28 upon which a valve 30 of inverted conical form is centered to releasably plug the valve port provided in the closure plate 31 at the bottom of the hopper.

The arrangement is such that when a predetermined weight of oversize solids accumulates in the hopper, the increased weight imposed on the sub-frame 16 will overbalance the adjustable 35 weights on the scale beams to tilt the scale beams in a direction tending to raise the link 24 and the outer end of lever 25. Thus, while the hopper moves downwardly, the link 24 is moving upwardly and the valve operating lever 25 will 40 thereby be caused to pivot sharply in a valve opening direction. The opening of the valve will allow the overweight solids to be discharged with only such water as lies between the particles of sand or other solids, and as soon as a sufficient 45 quantity of solids has been discharged to affect the weight of the hopper, the parts will move in directions reverse to those just described, with the result that the valve will again seat upon plate 31. The pivotal mounting of the valve enables it to center itself in the opening despite any displacement which may be occasioned during or because of the discharge of solids thereover.

The water or other liquid bearing solids to be classified is supplied through a flume 33 tangent- 55

tial to a volute delivery chamber 34 having an opening 35 in its bottom through which the whirling material is discharged into a partially submerged pan 36, the sides of which are only 5 slightly above the level of liquid in bowl 6 as determined by the height of wall 7. This pan has radial baffles 37 supporting it from a casing sleeve 38 which is rotatably carried by suitable bearings (not shown), from a vertical shaft 39, with 10 respect to which the pan is free to turn. The pan is rotated by engagement of its baffles 37 by the whirling mass of liquid and water borne solids delivered to the pan from the volute delivery chamber 34.

15 The pan also has an opening in its bottom at 40, this opening being submerged. An apertured baffle disk 41 on shaft 39 is positioned immediately below the opening 40 to dissipate the incoming material uniformly in all directions.

20 The incoming material reaches the classifier bowl while still in rotation, and the distributing baffle system is intentionally so designed that it does not materially impede the rotative movement of the liquid. Thus a broad slowly rotating 25 vortex is established throughout the classifier bowl through the use of the energy of the incoming liquid. The movement of this vortex is, however, so slow that it does not in any measure impair the settling out of the oversize product to 30 the bottom of the classifier bowl.

It is desirable that this deposit in the classifier bowl be kept at substantially a constant level in order that the flow of liquid thereover to the margin of the bowl may be as nearly uniform as 35 possible. At the same time it is necessary to move the deposited oversize product to the discharge hopper 15 with a minimum of disturbance of the liquid.

To accomplish these results I drive shaft 39 from motor 43 through suitable reducing gearing 40 at 44, and I mount on the shaft a set of radial supporting arms 45 and helically disposed raddles 46 which turn with the shaft at substantially the same rate at which the vortex rotates in 45 the classifier bowl. Since the raddles are moving with the water, substantially no eddy currents will be formed behind any of the raddle blades 46. At the same time each of the raddles has a helical pitch such that the solid oversize particles encountered by the raddle blade at the bottom of the classifier bowl will be progressively moved for a distance equal to the pitch and extent of the blade toward the sleeve 10 which affords communication with the discharge hopper 50 55 15. At their inner ends the arms 45 may conveniently be mounted on the plate 48 supported by a collar 49 on shaft 39. The arms preferably have an upward inclination of about ten degrees and at points at or near their outer ends they are supported by tie rods 50 which connect them with another collar 51 higher up on the shaft. The arms may also be braced from each other by tie rods 52.

Any suitable structure may be employed for the 60 support of the parts designated. That shown in the drawings is purely illustrative.

The invention from the standpoint of method 65 consists, first, in employing the kinetic energy of the delivered material to establish a vortex in the classifier bowl, the oversize product being allowed to settle out and come to rest in the bottom of the bowl while the vortex movement of the liquid in the bowl continues. Secondly, by reason of such movement, the relatively non-rotating solids 70 75 are moved centrally along the bottom of the

bowl by moving the raddle blades with the liquid but against the precipitated solids. Thirdly, the solids are discharged automatically from a hopper of relatively small capacity without moving the major content of the bowl or affecting continued classification therein. 5

The deposited solids are progressively advanced toward the center of the bowl while the classifying operation continues uninterrupted and unimpeded and under substantially uniform conditions. When the solids reach the opening in the bottom of the bowl they pass through the sleeve 10 into the discharge hopper which, being small in diameter as compared with the bowl, can be guided more readily for movement on the scale 15 mechanism and also will require but little space. Since a certain angle or pitch of hopper wall must be used, the depth or vertical dimension of the hopper can be kept to a minimum by reducing its diameter to a minimum. 20

The opening movement of the valve is accelerated as compared with the downward yielding of the hopper on the scale balance. Consequently the valve moves a much greater distance than the hopper, opening or closing rapidly. In operation the valve will assume a position open approximately enough to discharge the tonnage being delivered. Its balanced condition will result in a slight oscillation but the discharge will be generally constant and equal to the tonnage of oversize 30 material in the feed.

It will be observed that the space between the sleeve 10 and the hopper constitutes an air trap. This prevents either the liquid or the separated solids from rising appreciably against the air pressure in the trap and, as a result, the diaphragm is protected from abrasion. Even if a slight leak occurs past the diaphragm, there will be little, if any, sand coming in contact with the diaphragm. 40

I claim:

1. A classifier comprising the combination with a generally circular bowl centrally apertured, of means associated with the apertured central portion of the bowl for weighing and discharging solids therefrom, independently of the accumulations of solids in the bowl proper, a rotatable rake system including raddle means helically pitched for the delivery of solids progressively toward the bowl outlet, and means for maintaining the liquid in the bowl in rotation in a vortex having substantially the same direction and rate of movement as said rake system, said last mentioned means comprising a delivery flume opening centrally into said bowl and having a centrally apertured volute portion with which said flume 50 communicates tangentially about the level of liquids in the bowl, and means partially immersed in the liquid of the bowl for receiving the whirling mass from the flume, and baffle means for distributing such mass toward the periphery of the bowl without preventing its continued vortex rotation. 55

2. In a classifier, the combination with a bowl of generally circular form having a central outlet, of a weighing discharge hopper having an annular diaphragm connecting it with said bowl about said outlet, a valve in said hopper, weighing mechanism supporting said hopper for yielding movement respecting the bowl upon the accumulation of a predetermined weight of material in the hopper, a discharge valve in said hopper provided with connections for actuating it in accordance with hopper movement upon said weighing mechanism, a driving shaft disposed substantially centrally in the bowl above the out- 70 75 75

let thereof, and a rake system including radial arms and helical raddle means carried thereby for rotation with said shaft and within the bowl, said raddle means being adapted to deliver pre-
5 precipitated solids toward said outlet, a flume having a volute delivery portion and a central discharge eye above the level of liquids in the bowl, a pan partially submerged in the bowl and positioned to receive material from said eye, said pan
10 having a central outlet below the level of the bowl and a baffle positioned between said pan outlet and the outlet of the bowl for distribution of

material throughout said bowl without interfering with its rotation, the communication of said flume with said volute delivery portion being tangential in a direction tending to establish the rotation in the bowl of material admitted thereto 5 at a rate and in the direction of rotation of said rake system, whereby classification in said bowl will be continuous without interruption by the movement of said rake system or the discharge of solids from said hopper. 10
